UNITED STATES PATENT OFFICE.

SAMUEL T. CORBITT, OF ENID, OKLAHOMA.

SIGN.

Application filed June 2, 1923. Serial No. 642,939.

To all whom it may concern:

Be it known that I, SAMUEL T. CORBITT, a citizen of the United States, residing at Enid, in the county of Garfield and State 5 of Oklahoma, have invented certain new and useful Improvements in Signs, of which the following is a specification.

This invention relates to an improved sign and seeks to provide a device which 10 will be suitable for cross country highways, city cross streets and parks, merchant or private advertising, contractors' signs, railroad danger signs or the like.

The invention seeks, as a further object, 15 to provide a sign having a negligible wind resistance and embodying a skeleton construction rendering all letters and characters of information readily visible and readable either directly or at an angle.

20 And the invention seeks, as a still further object, to provide a sign which will be characterized by structural simplicity and yet will possess entire rigidity and durability.

Other and incidental objects will appear 25 hereinafter.

In the drawings:

Figure 1 is a side elevation of my improved sign,

30 Figure 2 is a fragmentary vertical sectional view on the line 2—2 of Figure 1, looking in the direction of the arrows,

Figure 3 is a fragmentary side elevation of a modified form of the invention,

Figure 4 is a horizontal sectional view on 35 the line 4—4 of Figure 3, looking in the direction of the arrows,

Figure 5 is a fragmentary elevation of a further modified form of the invention,

Figure 6 is a vertical sectional view on 40 the line 6—6 of Figure 5, looking in the direction of the arrows,

Figure 7 is a fragmentary elevation of a still further modified form of the invention,

Figure 8 is a detail elevation showing a 45 modified form of arrow,

Figure 9 is a fragmentary elevation showing a still further modification,

Figure 10 is a detail sectional view showing a slight modification in the mounting 50 of the sign characters.

In carrying the invention into effect, I employ a post 10 and mounted upon the post is a split ring 11 provided at its extremities with flanges 12 lying at opposite 55 sides of the post, bolts 13 being arranged to extend through said flanges and through

the post for securing the ring in position. The ring is preferably formed of a T-iron and is thus provided at its inner circumference with a flange 14, and extending horizontally within the ring are transverse bars 15 secured at their ends to said flange. These bars are designed to support the letters 16 of any desired sign word, as for instance, the name of a street, road or the like. Formed on or otherwise secured to the ring at its upper side is a spacer 21 and mounted upon said spacer is a horizontally disposed arrow 22 secured in place by rivets or other suitable fastening devices 60 extending through the spacer and through the ring. The arrow is cut away centrally to define spaced parallel bars 23 and mounted between said bars are the letters 24 of a suitable direction indicating word such, 65 for instance, as the word South, as illustrated. Arranged above the arrow 22 is a somewhat smaller arrow 25 pointing in a direction opposite to the former arrow. Spacers 26 are interposed between the 70 arrows and extending through said spacers are rivets or other suitable fastening devices 75 securing the arrow in position. The arrow 25, like the arrow 22, is cut away to provide spaced parallel bars 27 and mounted 80 between said bars are the letters 28 of a suitable direction indicating word such as the word North, as illustrated.

In order that the sign may be employed at the intersection of streets, roads or the like, 90 I further provide, as shown in Figure 2, aligned arrows 29 and 30. These arrows are similar to the arrows 22 and 25 but at the tail ends thereof are provided with mating bowed portions 31 to embrace the upper end 95 of the post 10 and extending through said bowed portions are bolts or other suitable fastening devices 32 connecting the arrows with the post to extend at right angles to the arrows 22 and 25. The arrows 29 and 30 are, 100 like the former arrows, cut away to provide spaced parallel bars 33 and mounted between said bars are the letters 34 of a proper direction indicating word upon the arrow 29 and the letters 35 of a proper direction indicating word upon the arrow 30, the words East 105 and West being illustrated. Thus, the sign may be employed to indicate the points of the compass. However, if preferred, the names of streets may be arranged upon the arrows 22, 25, 29 and 30, while suitable data 110 regarding roads or information as to the

distance of nearby towns or cities may be arranged within the ring 11. Also, if desired, this space may be employed for advertising purposes. It will, of course, be understood that the letters or characters giving information are detachably mounted so that said letters may be easily removed and other letters substituted for giving different or new information. Preferably, each of the arrows is 10 cut away at the head thereof to define an ornamental star, as illustrated, and to enhance the attractiveness of the sign. I preferably use the colors red, white and blue in painting the device. The top of the post 10, the 15 ring 11, the cross bar 15, and the bodies of the arrows are preferably colored blue, the top and bottom rails and tails of the arrows are preferably colored red, with alternate red and white stripes through the tail of each 20 arrow. The stars and the points of the arrows, as well as all letters and characters used, are preferably colored white.

In Figures 3 and 4, I have illustrated a modified form of the invention wherein I 25 employ a tubular post 36. Threaded upon the upper end of the post is a segmental block 37 secured by a lock nut 38 and rising from the block in alignment with the post is a socket 39 to removably accommodate an 30 electric lamp 40, current being supplied to the lamp by wires extending upwardly through the post. Mounted upon the block 37 is a split ring 41 provided at its ends with flanges 42 overlying the ends of the 35 block and arranged within said ring in eccentric relation thereto is a somewhat smaller split ring 43 provided at its ends with flanges 44 overlying the flanges 42. Extending through said flanges and through the 40 block are rivets or other suitable fastening devices 45 securing the rings in position. The rings are formed of T-iron and are thus provided with confronting flanges 46, and extending between said flanges at the end 45 portions of the rings are tie straps 47. Removably mounted between the rings are appropriate sign letters or characters typified at 48 and secured to the flanges 46 of the rings above the straps 47 are pairs of parallel bars 49 mounting sign letters or characters 50, the bars 49 being similar to the bars 15 previously described.

In Figures 5 and 6 of the drawings, I have 55 illustrated a further modification of the invention for use in connection with the modified structure of Figures 3 and 4. In the modification of Figures 5 and 6, I employ a post 51 like the post 36 and threaded upon the upper end of the post is a segmental block 52 secured by a lock nut 53. Secured to the ends of the block are inner and outer rings 54 and 55 identical with the rings 41 and 43 but of larger radius. These rings are provided at their ends with superposed 60 flanges 56 secured to the block by rivets 57

and connecting the end portions of the rings are tie straps 58. Mounted between the rings are appropriate sign characters typified at 59, and extending between the rings are parallel bars 60 for mounting similar characters. 70 Formed in the block 52 is a notch 60 to accommodate the block 37 of the modified structure of Figures 3 and 4 so that the latter block with its rings 41 and 43 may be positioned within the ring 54 extending at 75 right angles to the plane thereof, the ring 41 fitting within the ring 54. A sign suitable for use at the intersection of streets or at the intersection of cross roads is thus produced and in mounting the block 37 the block is, as best brought out in Figure 6, threaded upon the upper end of the post 51 along with the block 52 so that the lock nut 53 will serve to bind both blocks in place.

In Figure 7 of the drawings, I have illustrated a further modification of the invention wherein I employ a tubular post 62 as in the prior modification, and threaded upon the post at its upper end is a segmental block 63 secured by a lock nut 64. 90 Mounted upon the block are inner and outer split rings 65, identical with the rings 41 and 43 previously described and secured in like manner. These rings are connected at their end portions by tie straps 66 extending between the flanges 67 of the rings and mounted upon said flanges between the rings are sign characters typified at 68. At the upper side of the outermost ring is a spacer 69 mounting a broken arrow 70 held by rivets or other securing devices fastening the arrow and spacer in position. The arrow 70 is similar to the arrow 22 of the first embodiment of the invention described and is provided with spaced side bars 71, the uppermost of which is split medially so that the end portions of the arrow extend in angular relation to each other. Mounted between the side bars of the arrow are sign characters typified at 72. Extending within the innermost of the rings are parallel bars 73 and mounted between said bars are sign characters typified at 74. As suggested, the word Danger may be arranged upon the arrow, the words Safety First between the rings, and the word Stop between the bars 73. An effective danger sign is thus provided for use at railway crossings or the like and, as will be appreciated, the broken arrow will, of itself, emphasize the word Danger. Upstanding from the block 63 are flanges 75 mounting a lantern 76 secured between the flanges by set bolts 77. If desired, a suitable annunciator such as an alarm bell, may be substituted in lieu of the lantern. In any instance where the sign is to be used for indicating danger at a sharp curve in a roadway, a curved arrow, as indicated at 78 in Figure 8, may be employed in lieu of the arrow 70, the arrow 78 120

being identical with the arrow 22 but being curved longitudinally.

In Figure 9, I have illustrated a still further modification embodying a sign for general advertising purposes. In this modification I employ a post 79 as in the first embodiment of the invention described and mounted upon the post is a split ring 80 provided at its ends with flanges 81 seating against opposite sides of the post, bolts or other suitable fastening devices 82 being employed to extend through the post and through said flanges for securing the ring in position. The ring is preferably formed of a T-iron and is thus provided at its inner circumference with a flange 83 and extending horizontally within the ring are spaced parallel bars 84 secured at their ends to said flange. These bars are designed to mount sign characters as typified at 85. Mounted at the upper side of the ring is a spacer 86 and mounted upon said spacer is an arrow 87 secured by rivets or other suitable fastening devices extending through the spacer securing the arrow and spacer in place. The arrow 87 is identical with the arrow 22 of the embodiment of the invention first described and is provided with spaced bars 88 between which are mounted sign characters typified at 89.

All of the sign letters or characters employed are mounted in like manner. It is important that the outlines of the letters or characters be clearly defined to the eye. I, therefore, form said letters or characters at their upper and lower ends with reduced lugs 90 provided at their extremities with hardened lateral ears to receive rivets or other suitable fastening devices mounting the letters or characters. Thus, the entire outlines of said letters or characters will be entirely visible.

In Figure 10, I have illustrated a slight modification of the invention wherein the T-irons, or slats, or cross bars, as the case may be, are formed with confronting beads 91 while the sign letters or characters, as typified at 92, are provided at their upper and lower ends with reduced resilient clips 93 to firmly embrace said beads. Thus, the sign letters or characters will normally be rigidly mounted while, at the same time, said letters or characters may be readily dis-

placed for changing the wording of the sign.

Having thus described the invention, what I claim as new is:

1. A sign including a block, split eccentrically disposed rings secured at their ends to the block, the rings being provided with means to receive sign characters in the space between the outer periphery of one ring and the inner periphery of the other, and a post mounting the block.

2. A sign including a post, a block mounted thereon and provided with a notch, split eccentrically disposed rings secured at their ends to said block and provided with means to receive sign characters in the space between the outer periphery of one ring and the inner periphery of the other, a second block mounted upon the post and accommodated in said notch to extend at substantially a right angle to said first mentioned block, and split eccentrically disposed rings extending within the innermost of said first mentioned rings and secured at their ends to the latter block, said last mentioned rings being provided with means to accommodate sign characters in the space between the outer periphery of one of such rings and the inner periphery of the other.

3. A sign including a block, and split eccentrically disposed rings secured at their ends to the block and provided with means to receive sign characters in the space between the outer periphery of one ring and the inner periphery of the other.

4. A sign including a block provided with a notch, split eccentrically disposed rings secured at their ends to said block and provided with means to receive sign characters in the space between the outer periphery of one ring and the inner periphery of the other, a second block accommodated in said notch to extend at an angle to said first mentioned block, and split eccentrically disposed rings extending within the innermost of said first mentioned rings and secured at their ends to the latter block, said last mentioned rings being provided with means to accommodate sign characters in the space between the outer periphery of one of such rings and the inner periphery of the other.

In testimony whereof I affix my signature.

SAMUEL T. CORBITT.
